United States Patent Office.

ADAM HEINZ, OF BUFFALO, NEW YORK, ASSIGNOR TO HIMSELF, JOHN L. FISHER, AND GEORGE J. MUNSCHAUER, OF SAME PLACE.

Letters Patent No. 100,034, dated February 22, 1870.

IMPROVED REFRIGERATOR.

The Schedule referred to in these Letters Patent and making part of the same.

I, ADAM HEINZ, of Buffalo, Erie county, New York, (assignor to myself, JOHN L. FISHER, and GEORGE J. MUNSCHAUER, of the same place,) have invented certain Improvements in Refrigerators, of which the following is a specification.

The nature of this invention relates to the construction and arrangement of the ice-box of a refrigerator, having a hoppered bottom, with a central opening or slot, and a large and a small trough underneath said slot, the small trough or gutter being located below the large one, for the purpose of catching the moisture accumulating upon the under side of the larger one, and both gutters being connected with the waste-pipe. In combination with the above, a removable platform drawer is supported upon rollers on the top of the hoppered bottom, for the reception of the ice.

Figure I is a vertical section of my improvements, the drawer being shown in its proper position within the ice-box.

Figure II is a transverse vertical section of the same, the drawer being partly drawn out.

Figure III is a perspective view of the drawer, when used separately.

Letters of like name and kind refer to like parts in each of the figures.

A A represent the walls of a refrigerator of any common and well-known construction.

B B are two inclined plates, which form the bottom of the ice-box. They are inclined toward each other, leaving a central slot between them, which extends from the front to the rear of the refrigerator.

Below this slot a trough or gutter, C, is so arranged as to catch the waste water as it passes down the hoppered bottom plates of the ice-box, and carry it to the waste-pipe g, in the rear of the refrigerator. This gutter is V-shaped in its cross-section, and is inclined toward the rear of the ice-box, terminating above the mouth of the waste-pipe.

A very narrow gutter, D, is secured in a position directly below the center of the gutter C, extending its entire length, and connecting with the mouth of the waste-pipe.

By means of the peculiar construction and arrangement of these gutters C and D, as well as the hopper bottom B, a very desirable object is attained. In refrigerators a great quantity of moisture accumulates

upon the surface of the metallic lining, which moisture collects in drops, and thus descends to the bottom of the refrigerator. The metallic parts composing the bottom of the ice-box are also subject to this accumulation of moisture, especially upon the under side thereof, and hence the contents of the refrigerator located below the ice-box are exposed to, and often spoiled or injured by the frequent drippings from said parts. To obviate this evil I construct the bottom of the ice-box as above described, collecting the moisture accumulating upon the under side of the hoppered bottom B B in the gutter C, and that accumulating upon the under side of the gutter C, in the narrow gutter D, carrying the whole of it off, together with the waste water, through the waste-pipe g.

E represents a removable platform drawer, which is provided with handles f f at each end, and is supported upon rollers h h in such manner that it may be either partially or wholly withdrawn from its position upon the bottom of the ice-box. Its shape, as shown in cross-section in Fig. I, may either be similar to the bottom B B, or it may be made in any other desired shape or form. In Fig. II it is shown as partly withdrawn, and projecting from the front opening of the ice-box in the shape of a platform. The ice is placed upon it, as represented, and then the drawer, with its load of ice, is returned to the ice-box.

In Fig. III the drawer is represented as entirely removed from the ice-box, when it may be used as a receptacle for ice, in transporting it from the ice-house, street, or other place from whence the refrigerator may have to be supplied, directly into the ice-box of the refrigerator, obviating in a great measure the necessity of handling the ice with ice-tongs or hands, as is now required for such transportation.

Claim.

I claim as my invention—

The combination and arrangement of the hoppered bottom B B, removable platform drawer E, and the gutters or troughs C and D, for the purposes and substantially as herein described.

ADAM HEINZ.
